(57) **CLAIM**

The ornamental design of a computing device display screen with graphical user interface for providing geographic-based service information, as shown and described.

DESCRIPTION

The FIGURE illustrates a computing device display screen with graphical user interface for providing geographic-based service information.

The broken lines, which depict the computing device and a portion(s) or element(s) of a graphical user interface, are provided for the purpose of illustrating environment and/or context, and form no part of the claimed design.
